United States Patent Office

Des. 193,154
Patented July 3, 1962

193,154

CUP

Herman Gartzman, 161 S. Poinsettia Place,
Los Angeles 36, Calif.

Filed Aug. 12, 1960, Ser. No. 61,710

Term of patent 3½ years

(Cl. D44—9)

FIG. 1.

FIG. 2.

FIG. 3.

FIG. 1 is a perspective view of a cup embodying said design, showing the front of the cup;

FIG. 2 is a perspective view showing the back of the cup; and

FIG. 3 is a side elevational view thereof.

I claim:

The ornamental design for a cup, substantially as shown and described.
